DOBBY CHAIN

Warren B. Harris, Millbury, Mass.

Application January 7, 1939, Serial No. 249,793

9 Claims. (Cl. 139—334)

This invention relates to dobbay chains which are used in various types of looms for controlling the pattern of the cloth.

In my Patent No. 1,199,546 of September 26, 1916, I have shown a dobbay chain of the double index type having cross bars of wood connected together by metal chain links, wherein the bars have two rows of staggered holes for reception of the pattern pegs. In order to attach the links thereto, it has been customary to bore holes, and to pass straight pieces of wire therethrough and shape their ends to form loops which attach to the links connecting with adjacent bars. That structure has many disadvantages, owing particularly to the fact that the bar has been made of wood. The pegs which determine the pattern of the cloth are made of iron slightly tapered and threaded with a coarse thread. The wooden bars are drilled with straight holes into which these tapered metal pegs are inserted. When the peg is turned as a screw, the thread of the pin cuts a corresponding thread in the wooden bar and thus serves to hold the parts in place. This requires that the wood be comparatively soft. Hence, if a peg is changed in position many times, this will wear the hole in the bar badly and thus require replacing the bar with a new one. Moreover, the tapered peg threaded into a non-tapered hole tends to split the wooden bar and particularly when inserted in the holes near the ends of the bar which are most used. The peg may also be twisted in too tightly or not be in proper alignment with the hole and thus again injure the wooden bar. These wooden bars are expensive for many reasons, such as the necessity for a skilled workman to pick out straight grained wood and avoid sticks having cross grains which break easily. Moreover, there are many operations involved in making these bars, including sawing the wood into slabs, shaping the sides by planer operations and cutting the beveled ends, drilling the peg holes and the link holes, putting in the link wires and bending the same. Any one of these may result in a defect which necessitates throwing away that particular piece. Also, the link wire must pass through the bar in a straight direction and not interfere with the holes in the bar or weaken the structure seriously. Hence, these wires do not give the maximum holding power and may slip in position, it being particularly desirable that they be not permitted to turn in the holes and thus throw the bars out of alignment. These, and various other defects are inherent in such constructions.

It is a primary object of my invention to overcome such disadvantages and to provide a dobbay chain made of bars and links so constructed and arranged as to give the maximum of efficiency and service. Further objects will be apparent in the following disclosure.

In accordance with my invention, I propose to make the cross bar of a molded plastic material, and particularly a synthetic resin, having the desired strength and other properties required and to attach it in the chain by linkage members which are positioned during the molding operation and may be so shaped and arranged that they will be immovably positioned and will hold the bars properly as required.

Referring to the drawing which illustrates this invention:

Fig. 1 is an isometric view of a portion of a dobbay chain, in which each cross bar has a single row of peg holes;

20

Fig. 2 is a section on the line 2—2 of Fig. 1;

Fig. 3 is a section on the line 3—3 of Fig. 1;

Fig. 4 shows one of the dobbay pegs;

Fig. 5 is a top plan view of one of the pegs;

Fig. 6 is a detail showing a different form of chain link;

Fig. 7 is a modification showing a double row of dobbay peg holes and a different form of attaching link; and

Fig. 8 is a fragmentary view of a further modification showing another form of eyelet.

In this construction, the cross bars are made of a plastic resinoid, such as cellulose acetate, sold on the market under the trade name of "Tenite," which is a synthetic moldable resin capable of being molded to a desired shape by means of heat and pressure. Various other materials, such as the "Bakelite" phenol-formaldehyde resinoids may be employed, or any other material which may be molded to the required shape and which is capable of being used with the screw threaded dobbay pegs to permit their ready removal and insertion as required. I also propose to form the dobbay peg holes in this bar during the molding operation, and particularly, to put the link attachment wires in position and to mold the plastic resin around these wires so as to hold them securely and permanently in place without interfering with the use or the insertion and removal of the dobbay pegs.

50

As shown in the drawing, the cross bar 10 may be made in any suitable shape, but as illustrated, it is provided with beveled sides 11 and beveled ends 12. Each bar is provided with a single row (Fig. 1) or a double row (Figs. 6 and 7) of holes 55

14 therein which are so shaped and arranged as to hold the dobby pegs 15. The holes 14 are preferably made slightly tapered, such as about 0.008 inch. The pegs 15, as shown in Figs. 4 and 5, are metal pins having substantially cylindrical ends 16 and a flange 17 which limits the inward movement of the peg and therefore locates it relative to the bar. The peg is also provided with a very coarse screw thread 18, and this 10 threaded end is tapered slightly and substantially to the same extent as is the hole 14 of the bar. Hence, when the dobby peg is inserted into the hole 14, it will fit correctly therein and may, because of its being slightly oversize, cut a 15 thread in the comparatively soft resinoid material and thus form its own securing means. The holes 14 are so located and positioned that the required number of pegs may be put in place, and it is intended that these pegs may be changed 20 from one hole to another as required to govern the pattern of the cloth being woven on the loom.

The bar shown in Fig. 1 has but a single row of dobby peg holes which are widely spaced apart; hence the link connection may be more 25 easily inserted in this type than in the form shown in Figs. 6 and 7 which have two rows of holes. In the simplified form of Figs. 1 and 2, the attaching link wire 20 may be shaped as a straight piece going through a hole in the bar 30 and the opposite and projecting ends of each of the links may be bent to form loops 22 arranged to be connected by link 23 with loops of the link wire of adjacent bars. The ends of the wire are preferably bent back far enough so that they 35 will be embedded in the resinoid substance of the bar and thus form closed eyelets from which the link 23 cannot escape. Since, the resinoid material of the bar is molded around the wire 20, the linkage will necessarily stay in position. It 40 is to be understood that these wires are suitably put in place in the mold, and the resinoid powder is poured around the same and compressed by means of heat and pressure to the desired shape. The peg holes 14 are simultaneously formed by 45 suitable cores located in the mold. Hence, the whole bar with its assembled link wires and peg holes may be formed inexpensively in a single casting operation.

The problem which has been met heretofore 50 in connection with wooden cross bars where double rows of staggered holes are used, is easily solved by this construction, as shown in Figs. 6 and 7. Since a straight wire, shaped and arranged as shown in Fig. 1, would be close to a dobby peg hole and thus weaken the structure 55 somewhat, I preferably shape these connecting wires as shown in order to give various advantages. The wire of Fig. 6, has a bent central portion 30 of a somewhat S-shape, so arranged and formed that it will not be close to any of the holes 14. Also, the free ends of the wire are bent in opposite directions to form the loops or eyelets 31 and 32 which are located substantially in alignment with the linkage eyelets of the other bars, as permitted by the bent portion 30, so that the tractive force of the linkage 60 is perpendicular to the center line of the bar.

The free ends of the wire shown in Fig. 7 65 may be substantially parallel with that portion 70 of the wire forming the opposite side of the eyelet, and these ends may be embedded in the bar to form the closed eyelets 33. As shown in Fig. 6, the outer ends 34 of the wires may 75 also be substantially S-shaped, so that each wire end lies at an angle to the normal tractive force.

Since the end is embedded in the bar, it interlocks with the resinoid material and thus aids further in holding the wire linkage in place. That is, the bent portions 30, 32 and 34 are all 5 S-shaped and these three parts of the wire will each resist the lateral pull on the wire loop and hold the wire rigidly in position. In every case, the centers of the eyelets are in alignment with the direction of travel of the chain, and there is no tendency for the chain bars to twist out 10 or 15 of position.

It will now be appreciated that since the bar is made of a molded resinoid it may be easily shaped as desired, and that the holes may be molded therein without the expense of the drilling operations heretofore required for wooden bars. In particular, the fastening wires which 20 pass through the bar may now be so shaped that they cannot pull out of place or change in position and they interlock with the resinoid 25 and make a strong and rigid structure. The wooden bars have necessarily required that the wire be straight throughout that portion located within the bar; hence such a wire cannot be permanently locked in place but may become 30 loose. Moreover, the molded bar permits the use of a linkage wire which is bent in any desired shape, and the wire may be arranged prior to the molding step in any location of maximum 35 advantage. Due to the wire having a crooked central portion and its ends embedded in the resinoid, and particularly to the wire ends being bent laterally as shown in Fig. 6, and due to the fact that the wire is reinforced and supported in position by the molded resinoid, there 40 is very little chance of the wire being deformed or pulled out of shape or location during use of the chain. The bar may be provided with threaded holes, and in that case the resinoid 45 may be of the infusible and very hard type. It is preferred, however, that the resinoid be slightly plastic so that the threads may be cut by turning the pegs therein like an ordinary wood screw. Since the steel peg is normally slightly tapered, the holes in the bar may be tapered to the same extent, so that the parts will fit 50 properly, whereas it would not be possible to drill a tapered hole in a wooden bar as heretofore made. The resinoid moreover is not affected by moisture and it keeps its shape under the standard conditions of use, as well as having a far 55 longer life than has the wooden bar heretofore used. Many other advantages are inherent in this structure.

The linkage wire passing through the cross 60 bar may be made in two separate pieces to form the oppositely arranged hooks, and the claims are to be interpreted as covering this equivalent construction. For example, as shown in Fig. 8, a cross bar 10 having two sets of holes therein 65 may have the hooks or eyelets 40 formed of substantially U-shaped bodies having outwardly turned ends 41 and 42. The ends 42 may lie between two holes in the opposite rows, while the ends 41 may be positioned between adjacent holes in the same row; or any other suitable arrangement may be made for properly positioning the parts. It is preferable that both 70 ends of the eyelet be embedded in the bar but one of the ends may be left free, if desired. The eyelet may take any suitable shape provided an end or portion thereof is embedded in the resinoid bar and interlocks sufficiently therewith to prevent its being pulled out of place.

It will also be understood, in view of the 75

above explanation, that other moldable materials may be substituted for the resinoid specified to exemplify the invention. For example, the cross bar may be made of aluminum or various alloys used in die casting operations. It is, however, desirable that this substance of which the bar is made be molded in place around the eyelet or hook which serves to fasten one bar to another in the dobby chain. That is, the linkage wire or eyelet is to be secured rigidly in position by the molding operation; hence it is preformed and placed in the mold prior to the insertion of the moldable substance, whether metal or resinoid, that is employed to form the bar.

It will be appreciated that one may make many modifications in this construction and that the above description is to be interpreted as illustrating the principles of the invention, as well as specific applications thereof, and not as limitations except as defined by the appended claims.

I claim:

1. A dobby chain comprising a set of cross bars connected together by links, each bar being made of a molded plastic substance and having tapered dobby peg holes therein arranged for receiving and being threaded by the pegs, and linkage members immovably secured in position without interfering with the peg holes which are arranged for fastening one bar in proper alignment with another.

2. A dobby chain comprising a set of cross bars connected together by links, each bar being made of a molded substance and having dobby peg holes therein and linkage eyelets immovably secured in position during the molding operation which are so shaped and located within the bar as to interlock therewith and prevent removal thereof.

3. A dobby chain comprising a set of cross bars and links connecting them in alignment, each bar being formed of a molded substance and having tapered holes shaped to receive a tapered peg and link members secured immovably in place by the molded resinoid which are bent within the cross bar and so shaped as to prevent their removal.

4. A dobby chain comprising a cross bar made of a molded substance having peg holes formed therein and a linkage member embedded within

the bar which has its central portion shaped to avoid passing closely to the peg holes and its outer ends bent and embedded in the bar and forming closed eyelets.

5. A dobby chain comprising a set of cross bars connected in alignment by linkages, each bar being made of a molded substance and having dobby peg holes therein, and linkage members immovably secured within the cross bar by the molding operation, each of which has a bent portion within the bar which prevents removal thereof and a hooked end embedded in the bar and forming a closed eyelet.

6. A dobby chain comprising a cross bar made of a molded substance having rows of staggered dobby peg holes formed therein and a linkage member having a central portion embedded in the bar without interfering with the adjacent dobby peg holes and located at an angle to the direction of tractive force and having its opposite ends embedded in the bar and shaped to form closed eyelets.

7. A dobby chain comprising a cross bar made of a molded substance having dobby peg holes formed therein and linkage members embedded therein at their central and end portions, each member being shaped to avoid the adjacent dobby peg holes and having its ends bent to form eyelets and further bent at an angle to the direction of tractive force.

8. A dobby chain comprising a set of linked cross bars made of a molded substance which have tapered dobby peg holes therein and linkage members embedded at their central and end portions in the bar in positions which avoid intersecting the peg holes, each member being shaped to provide a central bent portion located between the peg holes and an outer loop forming a linkage eyelet having its free end bent at an angle to the direction of the tractive force involved in using the chain, so that deformation and removal of the linkage member is resisted.

9. A dobby chain comprising a cross bar made of a molded substance having dobby peg holes therein and separate opposed linkage eyelets having hooked ends embedded in and interlocking with the resinoid.

WARREN B. HARRIS.
